HIGH FREQUENCY COUPLING APPARATUS

Mendel Osnos, Berlin, Germany, assignor to
 Telefunken Gesellschaft fur Drahtlose Tele-
 graphie m. b. H., Berlin, Germany, a corpora-
 tion of Germany

Application June 8, 1931, Serial No. 542,731
 In Germany June 20, 1930

4 Claims. (Cl. 175—359)

This invention relates to high frequency coupling apparatus and especially to a transformer or coupling coil for ultra-short waves.

In working with ultra-short waves, the losses occasioned in metallic conductors subject to the influence of fields of extremely high frequency or to the flow of currents of these frequencies are very high. This results in serious difficulties in the attempt to use transformers or coupling 10 coils in apparatus operating with ultra-short waves.

According to this invention, these difficulties are overcome by using gaseous-discharge tubes to act as the conductor turns of transformers or 15 coupler coils, said tubes being preferably made coil-shaped. The number of turns contained in the primary and the secondary member may be chosen at will to suit the desired transformation ratios. The losses occasioned in tubes acting as 20 conductor turns of this kind are practically independent of the frequency and are relatively small.

One embodiment of the present invention is shown by way of example in the drawing. Referring to the same *p* and *s* denote two gas-discharge tubes which may consist of glass, quartz, or equivalent non-conducting material, and which contain a highly rarefied gaseous atmosphere such as neon, and which represent two 30 transformer windings, say, the primary and secondary. The relative position may be stationary or variable. Thus, they may be made slidable over one another, or, they may be made to rotate relative to each other thereby varying the 35 coupling. That is, the coils, similar to metallic coils, may be positioned adjacent, superposed or interposed, and they may be circular or flattened in form.

A high frequency generator and modulator 2 40 may be connected across the primary electrodes 4, and the output of the secondary may be fed to a suitable antenna 6. If desired, between the antenna 6 and secondary *S* there may be inserted a suitable amplifier (not shown).

45

Moreover, the coils may be immersed in a cooling fluid, such as oil or water and the fluid may be either stationary or flowing.

It is not necessary that a primary and secondary coil be provided, for, a single coil may be used having auto-transformer connections. That is to say, an additional electrode or electrodes may be inserted along the length of the tubular coil and the coil connected in the fashion of known auto-transformer arrangements. 65

Having thus described my invention, what I claim is:

1. In a system for transforming high frequency currents comprising a transformer especially adapted for short waves, having primary 70 and secondary low loss coils, each of said coils comprising a hollow quartz tube filled with an ionized gas, an input circuit coupled to electrodes of the primary coil, and an output circuit connected to electrodes of the secondary coil. 75
2. In a system for coupling ultra high frequency currents comprising a coupling coil, said coil composed of a hollow quartz insulating tube, said hollow insulating tube containing an ionized gas to form an ionized conducting stream for the 80 transfer of electric energy.
3. An ultra high frequency coupling coil especially adapted for short waves, comprising two low loss coils composed of hollow quartz insulating tubes, said tubes containing an ionized gas 85 forming a conductor to transfer energy from an input source of high frequency to an output antenna circuit.
4. An ultra high frequency coupling device especially adapted for short waves, comprising two 90 low loss coils in coupling relation to each other, each of said coils composed of insulating quartz tubes containing an ionized gas forming a conductor to transfer energy from an input source of high frequency to an output antenna circuit. 95
